OR D 18,774

DESIGN.

W. H. WILKINSON.

COOKING STOVE.

No. 18,774.

Patented Nov. 27, 1888.

UNITED STATES PATENT OFFICE.

WILLIAM H. WILKINSON, OF ROCHESTER, NEW YORK, ASSIGNOR TO THE BRIDGE AND BEACH MANUFACTURING COMPANY, OF ST. LOUIS, MISSOURI.

DESIGN FOR A COOKING-STOVE.

SPECIFICATION forming part of Design No. 18,774, dated November 27, 1888.

Application filed January 9, 1888. Serial No. 260,228. Term of patent 7 years.

To all whom it may concern:

Be it known that I, WILLIAM H. WILKINSON, now of Rochester, New York, formerly residing in the city of St. Louis, Missouri, have 5 invented and produced a new and original Design for Cook-Stoves, of which the following is a specification, reference being had to the accompanying engraving, forming part thereof, in which the newly-designed stove is shown in 10 perspective.

The stove A, generally considered, is of a familiar type, its body a^1 being cubiform, supported upon legs a^2 , having a hearth, a^3 , and a square top, a^4 .

15 The leading feature of the design is an ivy ornamentation appearing upon the side of the stove, as follows: Upon the oven-door a^5 is an escutcheon, B, consisting of the face b and the surrounding circular border, and surrounding 20 the escutcheon is a wreath, C, of ivy, which at c is extended in the form of a spray. The remaining portion of the door presents a smooth appearance, and the door, as a whole, projects prominently from the side plate of the stove.

25 A cluster, D, of ivy appears upon the fire-place door a^6 , which otherwise has a smooth plain finish. The door a^6 is square in outline, and the panel a^7 , bearing the cluster D, projects noticeably outward. Upon the legs is a 30 lion's face, E, terminating below in an ivy ornamentation, e. The border G, like the outline of the leg, is widest above and tapers to its lower end. At the upper end the border

is in the form of flutings g , and the remaining portion of the border is in the form of bead-work g' . The face E in side elevation projects markedly from the surrounding portion of the leg.

I claim—

1. The design for a cook-stove herein shown and described, the same consisting of the body, the legs, and the escutcheon, composed of the face and the encircling border and surrounded by the ivy wreath extended to form a spray upon the oven-door and the cluster of ivy upon the fire-place door. 40
2. In a design for a cook-stove herein described and shown, the oven-door, projecting as shown, and provided with ornamentation consisting of the escutcheon and the surrounding ivy wreath extended in the form of a spray. 45
3. In a design for a cook-stove the square projecting fire-place door herein shown and described, and provided with ornamentation consisting of the cluster of ivy. 50
4. In a design for a cook-stove, the tapering leg having the projecting face surrounded by the border composed of the flutings, cluster of ivy, and bead-work, as herein shown and described. 55

Witness my hand.

WILLIAM H. WILKINSON.
